SPARK PLUG

George C. Brinker, Greensburg, Pa.

Application March 23, 1935, Serial No. 12,721

1 Claim. (Cl. 123—169)

My invention relates generally to spark plugs, and particularly to a ventilated and cooled non-fouling spark plug for use in ordinarily internal combustion engines, and an important object of my invention is to provide a novel arrangement and construction of body, insulator or core, and electrodes whereby the insulator and the main electrode are kept at a cooler temperature so as to reduce the rate of deterioration of the spark plug and provide for more efficient operation.

Another important object of my invention is to provide in a spark plug an arrangement of electrodes or sparking points whereby thru the mechanical activity of one electrode, accumulations of oil and the like thereon are mechanically removed so as to be prevented from attaching and fouling thereon, and to provide a greater than usual number of points.

Other objects and advantages of my invention will be apparent from a reading of the following description in connection with the drawing, wherein for purposes of illustration I have shown a preferred embodiment of my invention. In the drawing:—

Figure 1 is a transverse vertical sectional view through an embodiment of the invention.

Figure 2 is a horizontal sectional view taken through Figure 1 approximately on the line 2—2 looking downwardly in the direction of the arrows.

Figure 3 is a bottom plan view of Figure 1.

Referring in detail to the drawing, the numeral 5 generally designates the body of the plug which is formed in its upper half with a relatively large bore 6 of uniform cylindrical cross section which leads into a downwardly tapering portion 7 whose largest diameter is smaller than the diameter of the bore portion 6 so as to define the shoulder 8.

The core or insulator which is generally designated 9 includes the portion 10 conforming in shape to the upper bore portion 6 and the lower tapering part 11 which is fluted as indicated at 12 at several points of its circumference so as to provide for the passage of cooling gases around and about the portion 11. The lower end of the part 10 of the plug is seated on a compression washer 13. The lower end of the portion 11 is approximately flush with the lower end of the body as shown.

One side of the body has a radial passage 14 which leads into a circumferential groove 15 on the exterior of the portion 10 of the insulator which provides for the circulation of cooling gases

and air around the adjacent portion of the insulator.

The upper part of the insulator above the portion 10 is reduced and tapered as indicated at 16 so as to define the shoulder 17 on which is arranged the compressible gasket or washer 18 which is compressed in place and the insulator forcibly engaged with the body portion by the screw cap 19 which threads on the exterior of the upper end of the body just above the laterally extending shoulder 20 below which the body is smooth as indicated at 21 to a point below the lower end of the bore 6. A reduced exterior portion 22 on the body defines the upper end of the spark plug hole engaging threaded portion 23 of the body which is received in the spark plug opening in the head of the engine.

Depending from the lower end at diametrically opposite sides of the body are the lugs 24 and 25 which have openings 26 and 27, respectively, to receive the reduced ends 28 and 29 of the spark point which is generally designated 30.

The sparking point 30 is composed of a shaft 31 which is provided at equal distances from its center with the disks 32, 33 which bound the reduced portion 34 and are so spaced and sized as to present at equal distances from the exposed lower end of the electrode 35 three different sparking points, represented by the adjacent side of the reduced portion 34 and the adjacent sides of the disks 32 and 33.

The reduced ends 28 and 29 of the sparking point 30 turn and laterally move in the openings in the lugs 24 and 25 upon agitation of the fuel mixture in the combustion chamber, in conjunction with the commotion of the gases in the fluted passages 12, so that the sparking point jumps up and down and rotates so as to mechanically throw therefrom any accumulations of oil or soft carbon, so that the sparking points are kept clean and better ignition is obtained. No end-play is permitted the sparking point 30.

The electrode 35 is a plain rod extending through an accommodating opening in the insulator to the point 36 where it is threaded and enlarged as indicated at 37 and threaded in a threaded opening in the top of the insulator portion 16 above which the electrode has the flange 38 from which projects the binding post 39 which receives the usual binding post nut (not shown).

Although I have shown and described herein a preferred embodiment of my invention, it is to be definitely understood that I do not desire to limit the application of the invention thereto,

and any change or changes may be made in the materials, and in the structure and arrangement of the parts, within the spirit of the invention and the scope of the subjoined claim.

5. What is claimed is:—

A spark plug of the type described comprising a body containing an insulator, said insulator having an electrode therein having an exposed

point at the lower end thereof, said body having a slideable and rotatable shaft disposed adjacent the exposed end of the electrode, and a pair of spaced integral disks on said shaft projecting from said shaft beyond the free end of the electrode and spaced therefrom. 5

GEORGE C. BRINKER.
